UNITED STATES PATENT OFFICE.

CATHRINE A. GRISWOLD, OF WILLIMANTIC, CONNECTICUT.

DESIGN FOR GARMENT-SUPPORTING HOOK.

Specification forming part of Design No. 5,225, dated August 22, 1871.

To all whom it may concern:

Be it known that I, CATHRINE A. GRISWOLD, of Willimantic, in the county of Windham and State of Connecticut, have invented and produced a new and original Design for Garment-Supporting Hooks, to be used upon corsets and for other purposes, of which the following is a specification:

The nature of my design is fully illustrated by the accompanying drawing, in which Figure 1 represents a front view of the hook, and Fig. 2 represents a side view of the same.

The hook is made in the form of an escutcheon, A, as shown, and the tongue B set up from its center, and three holes, a, are formed in a triangular position in the upper part of the escutcheon to receive the rivets by which it is secured in position. Openings b are formed in the lower part,

at the root of the tongue, and said tongue is ornamented with a leaf pattern springing from the lower center, as illustrated. The metal at the edges of the escutcheon and around the various openings is set up so as to form a plain narrow border, c, while the intermediate surface d is pebbled or roughened, all of which is fully shown in the drawing, the whole producing, when finished in nickel or silver plating, a very neat, brilliant, and beautiful design.

I claim—

The design for garment-supporting hook, substantially as shown in the drawing and herein described.

CATHRINE A. GRISWOLD.
